UNITED STATES PATENT OFFICE.

ELIZABETH M. McCOLLUM, OF CHICAGO, ILLINOIS.

DRESSMAKER'S SKIRT SCALE AND GUIDE.

No. 807,308.

Specification of Letters Patent.

Patented Dec. 12, 1905.

Application filed April 26, 1905. Serial No. 257,480.

To all whom it may concern:

Be it known that I, ELIZABETH M. McCOLLUM, a citizen of the United States, and a resident of Chicago, in the county of Cook and 5 State of Illinois, have invented certain new and useful Improvements in Dressmakers' Skirt Scales and Guides, of which the following is a specification.

This invention relates to a dressmaker's skirt 10 scale and guide, and more particularly to a device adapted for use by dressmakers and fitters in measuring and adjusting the lower edge of a skirt so that it will hang the same distance from the floor all the way around. 15 Among the salient objects of the invention are to provide a device of the character referred to which is adjustable, neat and simple, and which can be readily disassembled and put up in a small package for shipment. 20 The invention will be readily understood from the following description, reference being had to the accompanying drawings, in which—

Figure 1 is a front elevation of the invention 25 with a portion of a skirt shown to illustrate the manner of using the device, and Fig. 2 is a sectional view taken on line 2 2 of Fig. 1.

In the drawings, 1 designates a base member supporting a standard 2, preferably screwed 30 thereinto and carrying at its upper end a detachable handpiece or ring 3. Slidably and detachably mounted upon said standard 2 is an arm 4, which can be locked in any desired position of adjustment upon said standard by 35 means of a thumb-screw 5. 6 designates a depending guide-frame carried by the outer end of said arm 4 and provided at its lower edge with a turned-up portion 7, forming a trough-like construction with a straight bottom member 7'.

8 designates a scale casing or frame vertically disposed and carried by an arm 9, secured to the standard 2, while 10 designates an inch-scale mounted within said frame.

45 The straight or lowermost member 7' of the depending guide-frame 6 is extended, as at 11, so as to serve as a pointer or indicator. Thus when the arm 4, carrying the guide-frame, is raised or lowered, the indicator 11 indicates

upon the scale 10 just how far from the floor 50 the guide-frame is.

The use and operation of the invention may be briefly stated as follows: The device is placed upon the floor at the side of the person to whom the skirt is to be fitted. The skirt 55 is then dropped down over the device until the lower edge thereof rests in the trough-like portion of the guide-frame, as at A, which of course has been adjusted to the desired height. The person standing erect then turns 60 around slowly while the dressmaker or fitter marks or turns up the lower edge of the skirt and pins it in the manner indicated in Fig. 1. The skirt thus adjusted will hang with its lower edge the same distance from the floor 65 all the way around.

While I have shown what I deem a preferred embodiment of the invention, it is obvious that modifications can be made therein without departing from the spirit of the invention, and 70 I do not, therefore, limit the invention to the details of construction and arrangement here shown except in so far as such details are made the subject-matter of specific claims.

I claim—

1. A dressmaker's skirt scale and guide comprising a base member, a standard mounted thereupon, arms mounted upon said standard, one carrying a vertically-disposed scale, and the other a guide-frame, provided with an indicator for indicating the height of said frame from the floor, substantially as described. 75

2. A dressmaker's skirt scale and guide comprising a base member, a standard mounted thereupon, an arm mounted upon said standard and provided with a vertically-disposed scale casing or holder, a scale mounted within said casing, an arm adjustably mounted upon said standard, a guide-frame comprising a wire skeleton frame having a straight 80 trough-like portion carried by said adjustable arm, and an indicator carried by said guide-frame for indicating the height of said frame from the floor, substantially as described. 85

ELIZABETH M. McCOLLUM.
